UNITED STATES PATENT OFFICE.

DAVID AUGSBURGER, OF BERNE, INDIANA.

EVAPORATING APPARATUS.

SPECIFICATION forming part of Letters Patent No. 622,319, dated April 4, 1899.

Application filed September 27, 1897. Serial No. 653,097. (No model.)

To all whom it may concern:

Be it known that I, DAVID AUGSBURGER, a citizen of the United States, residing at Berne, in the county of Adams and State of Indiana, have invented a certain new and useful Improvement in Evaporating Apparatuses, of which the following is a specification.

My invention relates to a new and useful improvement in evaporating apparatuses, and has special relation to such devices for the cooking of molasses, for the purpose of evaporation in thickening molasses, or in making sugar and the like by steam heat, whereby the temperature may be so regulated as to prevent overheating, yet permit a constant action upon the molasses until the operation is finished; and a further object of my invention is to provide for the transference of the material being treated from one compartment to another through a series of such compartments, whereby the material may be retained in various degrees and transferred from one to the other until the operation is completed; and a still further object of my invention is to so construct the steam-compartments of the apparatus as to provide for the heating of certain of the reservoir-compartments to various degrees to correspond with the various stages through which the material passes.

With these objects in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming part of this specification, in which—

Figure 1 is a plan view of improvement; Fig. 2, a section at the line xx thereof; Fig. 3, a section at the line yy of Fig. 2, and Fig. 4 a section at the line zz of Fig. 3.

In carrying out my invention as here embodied I provide a reservoir-tank A, which may be of any desired size or shape, and this tank is divided into several compartments B to B^3 by means of the partitions C, which latter extend crosswise of the reservoir-tank, each having an opening D therethrough,

adapted to be closed by the slide-gate E, by which arrangement the material being operated upon may be first placed in one of these compartments and there retained until properly treated for that particular stage, after which it may be transferred to the next compartment by the opening of the gate E and again treated, from which it may be withdrawn by any suitable means. This tank rests upon the heating-casing F, which is also divided into a series of compartments G to G^4 by the partitions H and I, the former extending part way across the interior of the casing, while the latter extend entirely across the same, thus dividing the casing into a series of double compartments, which are subdivided by the partitions H, as clearly shown in Fig. 3. The casing F has top J thereon, through which are a series of holes K, so that while the top surface is a support for the bottom of the reservoir-tank a large proportion of the surface of this bottom is exposed to the direct action of the steam admitted to the heating-casing, thus facilitating the treatment of the material contained within the tank.

A supply-pipe L, leading from a suitable steam source, runs parallel with the apparatus and has the branch pipe M and M' leading therefrom, in which are located the valves N, and these last-named pipes communicate with the compartments G' and G^3 of the heating-casing, as clearly shown in Fig. 3, so that when steam is admitted therethrough it will enter said compartments and pass around the partitions H to the compartments G^2 to G^4 , after which it passes from the casing by means of the branch pipe P, and suitable valves Q are arranged in the last-named branch pipe for regulating the outflow of this steam. After the steam passes from the compartments G^2 and G^4 to the pipe P it flows from thence to the compartment G, as indicated by the arrow a, and this exhaust-steam in circulating through the compartment G serves to heat to a certain extent the cold material which may be in the division B at this time, thereby avoiding the wasting of any heat and preparing the raw material for the next step in the treatment, which takes place after it has been transferred to the compartment B' . The steam is entirely exhausted from the appa-

ratus through the pipe R', the outflow through which is controlled by a suitable valve.

From this description it is obvious that a slow and continuous heat may be transmitted 5 to the material contained within the reservoir-tank and that various degrees of heat may be transmitted to different parts of said tank, so that the molasses or other material contained therein may be properly treated in 10 its various stages until the operation is finally completed, after which it may be drawn from the tank, as before stated.

The waters of condensation which accumulate 15 within the compartments G to G⁴ may be drawn therefrom by the drain-pipes R, and these pipes have located therein the valves S for preventing the outflow of the steam from the compartments when this is not necessary.

I have found in practice that molasses may 20 be so treated as to produce a superior result by the use of my apparatus than when treated in any other manner, since it need be never overheated, and yet at all times be held at the proper temperature for producing the most 25 advantageous results.

Having thus fully described my invention, what I claim as new, and desire to secure by Letters Patent, is—

1. In combination, a reservoir-tank, partitions for dividing the same into compartments said partitions having openings therethrough, gates for closing said openings, a

heating-casing a perforated top therefor, partitions H and I, located within the heating-casing whereby it is divided into compartments which are subdivided, induction-pipes leading to the heating-casing compartments and exhaust-pipes leading therethrough, substantially as and for the purpose set forth. 35

2. In combination a heating-casing, partitions I, arranged therein for dividing its interior into compartments, partitions H, also arranged therein for subdividing said compartments, induction - pipes leading to the compartments, exhaust-pipes leading there- 40 from, a valve for controlling the inflowing and outflowing of the steam, drain-pipes leading from each of the compartments, valves connected therewith for regulating the outflow through these drain-pipes a perforated 45 top for the heating-casing, a reservoir-tank located thereon, partition C, for dividing the tank into compartments, said partitions having holes therethrough and gates for closing said openings, substantially as and for the 50 purpose set forth.

In testimony whereof I have hereunto affixed my signature in the presence of two subscribing witnesses.

DAVID AUGSBURGER.
